United States Patent Office

Des. 206,340
Patented Nov. 29, 1966

206,340

CUP

Roland W. Gregory, Commerce City, Colo.
(7531 Niagara St., Denver, Colo. 80216)

Design application Mar. 9, 1964, Ser. No. 79,163, now Patent No. 203,054, dated Nov. 30, 1965, which is a continuation of design application Ser. No. 69,443, Mar. 26, 1962. Divided and this application Oct. 12, 1965, Ser. No. 460

Term of patent 14 years

(Cl. D44—9)

FIG. 1

FIG. 2

FIG. 3

FIG. 4.

FIG. 6.

FIG. 5.

FIG. 1 is a perspective view, taken from the right side, of a cup embodying my new design;

FIG. 2 is a perspective view, taken from the left side, of the cup of FIG. 1;

FIG. 3 is a perspective view, taken from the rear, of the cup of FIG. 1;

FIG. 4 is a perspective view, taken from the left side, of a cup similar to the cup of FIG. 1 but having a variation in the handle;

FIG. 5 is a perspective view, taken from the rear, of the cup of FIG. 4; and

FIG. 6 is a perspective view, taken from the right side, of a cup similar to the cup of FIG. 4 but having the handle reversed in position.

This application is a division of my earlier filed application Serial No. D.79,163 of March 9, 1964, now Patent

Des. 203,054 of November 30, 1965, which application was a continuation of my earlier filed application Serial No. D.69,443, filed March 26, 1962, now abandoned.

I claim:

The ornamental design for a cup, as shown and described.
